DOUBLE THROW SWITCH

Filed Aug. 14, 1928

UNITED STATES PATENT OFFICE

CHARLES L. BUGBEE, OF WESTMONT, NEW JERSEY, ASSIGNOR OF ONE-HALF TO
COLUMBUS STAMPER, OF PHILADELPHIA, PENNSYLVANIA

DOUBLE-THROW SWITCH

Application filed August 14, 1928. Serial No. 299,519.

This invention, generally stated, relates to electric switches, and has more especial relation to the type known as a double-throw electrical switch.

5 In a double-throw electrical switch it is necessary that at certain periods the operating lever be positively maintained in neutral position so that accidental flow of current through either knife blade is reduced to a minimum.

While heretofore so-called center stops for double throw electrical switches have been devised, commercially considered, the same have proven either impracticable, inefficient, or too costly to manufacture.

One object of the present invention is to overcome the above described disadvantageous features and provide a novel form of construction of double-throw, quick break 20 type of electrical switch of simple, efficient, and comparatively inexpensive structure in which the switch blades are pivoted in a special manner for cooperation with a unique form of center stop.

25 Other and further objects reside in the provision of general details of construction and in the arrangement and combination of parts for attaining the results sought by the foregoing objects.

30 With these and other objects in view, the invention consists of the novel construction hereinafter described and finally claimed.

The nature, characteristic features and scope of the invention will be more fully understood from the following description taken in connection with the accompanying drawings forming part hereof, and in which:

Fig. 1, is a view in side elevation of a double-throw electrical switch embodying the invention.

Fig. 2 is a view in section taken upon the line 2—2 of Fig. 1; and

Fig. 3, is a view in section taken upon the line 3—3 of Fig. 1.

45 For the purpose of illustrating my invention I have shown in the accompanying drawings one form thereof which is at present preferred by me, since the same has been found in practice to give satisfactory and reliable results, although it is to be understood

that the various instrumentalities of which my invention consists can be variously arranged and organized and that my invention is not limited to the precise arrangement and organization of the instrumentalities as 55 herein shown and described.

Referring to the drawings in detail, the reference numeral 1 designates a base of insulating material upon which are secured the switch terminals 2 and 3 which switch terminals are shaped to alternatively receive the blade of a double-throw knife switch. Fixed to and projected outwardly from the base 1 is a block 4 of insulating material fixed to which, as by means of a screw 5, is a metallic 60 member to pivotally accommodate the double-throw knife switch and comprises a support 6 and a bifurcated part 7 extended at right angles therefrom. The blade 8 of the double-throw knife switch has central, pivotal relation at 9 with the bifurcated part 7 of the support 6. The blade 8 is carried by a relatively narrow member 18 of insulating material comprised of an arched outer portion 10 and an inner straight portion 11, the latter 65 being grooved at 12 to accommodate the blade 8. The blade 8 is secured in place by means of screws 13. The reference numeral 14 designates an operating handle fixed to member 18. Fixed to each side of the arched member of insulating material 18 is a thin metal plate 15 the outer edge of which is arched at 16 and the inner edge 17 of which is straight, this arrangement conforming to the configuration of the member 18 and 70 adding to the compactness and appearance of the switch lever. Each plate 15 is provided with a central counter-sink 19 arranged in with the longest axis of the operating handle 14, the purpose of which will presently 75 appear. Fixed to base 1, as by screws 20, and extended outwardly therefrom at right angles thereto, are spaced, parallel arms 21. These arms 21 at their outer ends are each provided with an inwardly extended boss 22. 80 Each arm and boss is horizontally bored to receive a ball 23 and a coiled spring 24 for impelling the ball inwardly. In the central or neutral position of the switch the counter-sinks 19 accept the balls 23 and thus inter- 85

lock the blade 8 against accidental movement. It is to be understood in moving the switch parts from neutral to either of the operative positions, that the balls frictionally engage or ride over the metal plates 15. The tension of each spring 20 may be regulated by a screw 25 arranged upon the same horizontal axis as the springs and bosses. Lock nuts 26 are provided for securing the screws 24 in adjusted position.

10 Having thus described my invention, what I claim as new and desire to secure by Letters Patent, is:

1. A double-throw switch comprising a base, a fixed, bifurcated member extended outwardly from said base, an arcuate oscillating switch lever of insulating material supported at the center of oscillation by said bifurcated member, a pair of spaced, metallic arcuate plates fixed to said switch lever, each plate being apertured for neutral alignment with the center of oscillation of said switch lever, parallel flat arms screwed to and extended outwardly from said base and provided at their outer ends with inwardly extended bosses each having a bore therein, an end-wise shiftable spring-pressed spherical member within each bore for engaging said apertures to maintain said lever in neutral position, a screw engaging each of said plates for adjusting the tension of each of said springs, and a lock nut for securing each screw in adjusted position.

2. A double-throw switch comprising a base, a fixed, bifurcated member extended outwardly from said base, an arcuate oscillating switch lever of insulating material supported at the center of oscillation by said bifurcated member, a pair of spaced, metallic arcuate plates fixed to said switch lever, each plate being apertured for neutral alignment with the center of oscillation of said switch lever, parallel flat arms screwed to said base and provided with inwardly extended bosses, horizontally arranged spring pressed detents arranged within said bosses for engaging said apertures to maintain said lever in neutral position, and an adjusting screw for tightening the tension upon said detents including lock nuts for adjusting said spring pressed detents.

CHAS. L. BUGBEE.
